UNITED STATES PATENT OFFICE

FRANK DEBSKI, OF NEW YORK, N. Y.

DESIGN FOR A CHAIR

Application filed December 7, 1929. Serial No. 33,694. Term of patent 3½ years.

To all whom it may concern:

Be it known that I, FRANK DEBSKI, a citizen of the United States, residing at New York, in the county of New York and State of New York, have invented a new, original, and ornamental Design for a Chair, of which the following is a specification, reference being had to the accompanying drawing, forming part thereof.

The figure is a perspective view of a chair, showing my new design.

I claim:

The ornamental design for a chair, as shown.

FRANK DEBSKI.
